CLAIM

I claim the ornamental design for a support for an intracardiac echocardiogram device, as shown and described.

DESCRIPTION

FIG. 1 is a front, top and right side perspective view of a support for an intracardiac echocardiogram device, shown in condition of use for clarity of disclosure;

FIG. 2 is a front, top and right side perspective view of the support for an intracardiac echocardiogram device of FIG. 1;

FIG. 3 is a top plan view thereof;

FIG. 4 is a bottom plan view thereof;

FIG. 5 is a rear side elevational view thereof;

FIG. 6 is a front side elevational view thereof;

FIG. 7 is a right side elevational view thereof; and,

FIG. 8 is a left side elevational view thereof.

The broken lines in the drawings depict portions of the support for an intracardiac echocardiogram device that form no part of the claimed design. The broken lines showing a catheter in FIG. 1 depict an environmental structure that forms no part of the claimed design. All broken lines form no part of the claim.

1 Claim, 8 Drawing Sheets
